UNITED STATES PATENT OFFICE.

NILS E. LINDBERG, OF SHOREHAM, NEW YORK, ASSIGNOR TO RADIO CORPORATION OF AMERICA, A CORPORATION OF DELAWARE.

INTERTRANSPOSITION OF SOUND AND ELECTRICAL ENERGY.

Application filed August 17, 1927. Serial No. 213,567.

This invention relates to the intertransposition of sound and electrical energy, and more particularly to an inertialess speaker for translating electrical energy to sound energy.

5 Ordinarily electro-acoustic devices possess mass and elasticity, and therefore experience mechanical tuning or natural resonance phenomena which are the cause of distortion in the sound or electrical wave produced. It is 10 clear that an ideal solution of the problem of distortionless reproduction may be obtained by the intertransposition of sound and electrical energy without the intermediate use of a vibratory device possessing either inertia or elasticity, and accordingly, it is an 15 object of my invention to obtain such intertransposition.

To do this I produce a corona discharge in the air medium which is to carry the sound, 20 and take advantage of the corresponding and related fluctuations of the pressure of the air, the heating effect of the corona discharge taking place therein, and the electrical energy producing the corona discharge. In the case 25 of a speaker the corona discharge device is energized by the use of unmodulated energy from some local source of direct or super audible alternating potential, and the corona is modulated by superimposing on the applied 30 potential energy of audio frequency or modulated energy of high frequency. The local energy, if alternating, must not only be super audible but must be of such frequency that it will not beat with the modulated carrier at 35 an audible frequency, that is, their frequencies should be equal, or should differ by a super audible frequency.

The invention is more fully described in the following specification which is accompanied by a drawing in which

Figure 1 indicates a corona speaker energized by direct current and modulated by audio frequency energy;

Figure 2 shows a corona speaker equipped 45 with a reflector, energized with direct current, and modulated by modulated high frequency energy;

Figure 3 is another view of the speaker shown in Figure 2;

50 Figure 4 represents the direct energization of a corona speaker by modulated high frequency energy;

Figure 5 shows the use of local high frequency energy to produce the corona discharge; and

Figure 6 indicates the use of a corona device as a microphone.

Referring to Figure 1 there is shown a metallic ball 2 which is studded with a large number of needle points, and which is brought to a high potential by a battery 4 through a power limiting resistance 6. The function of this resistance is to prevent injury in case someone touches the discharge sphere. The corona draws but slight current, and the normal potential drop across the resistance is small, but upon accidental grounding there is an increase of current which causes a marked decrease in the potential applied to the sphere.

The corona effect is aided by the proximate juxtaposition of a grounded plate 8, in which the lines of force terminate. Signal energy received on an antenna 10 is rectified by a detector tube 12, the audio frequency output of which is fed to an amplifier 14, from which the audio frequency energy is superimposed on the direct energy from the battery 4 through the medium of a transformer 16, thus serving to modulate the corona discharge.

One advantage of the speaker described is that it is directionless, but if a directional speaker is desired the grounded shield may be made in the form of a parabolic reflector, as is indicated in Figure 2. Referring to this figure the corona discharge sphere 2 is located at the focus of a parabolic reflector 18, which is metallic and grounded to terminate the corona lines of force, and which preferably is surrounded by a heavy backing of rubber or other damping medium 20, in order to make the reflector substantially aperiodic. This is in contrast to the use of a horn, for even the mass of the air column in a horn is to be avoided.

In this case, as in the modification shown in Figure 1, the energization is by means of a direct current source 4, but the modulation is obtained directly at radio frequency, signals being picked up on antenna 10 and amplified at radio frequency in an amplifier 22. The direct current source may merely bring the potential up to the critical corona discharge point, if desired, but this is not essential for rectification, because the corona phenomenon is one of heating, and depends on the current squared, and therefore the device is inherently rectifying.

In Figure 4 the modulated high frequency energy picked up by the antenna 10 and am-

plified in amplifier 22 is fed to a corona speaker 2 and serves not merely for modulation of the corona, but actually produces it.

In the modification shown in Figure 5 there is a local source of high frequency energy 24 which serves to energize the corona sphere 2, and modulation is obtained, as before, by means of audio frequency or a modulated radio frequency. In the latter case the radio frequencies should either be arranged to homodyne, that is, their frequencies should be exactly equal, or else should differ by a super-audible frequency so that an audible beat will not be produced, which would otherwise spoil the reproduction. In case single side band energy is received the oscillator 24 may be used to supply the carrier energy.

In Figure 6 there is indicated a corona sphere 2, situated at the focus of a parabolic reflector 18, and energized by a direct current source 4. In this case the corona discharge device is used as a microphone, and sound directed towards the reflector will vary the air pressure in which corona is taking place, and therefore vary the energy consumed in producing the corona. This energy fluctuation may be coupled through a transformer 16 and led to suitable amplifiers before being used for wire transmission or for modulating high frequency energy for radio transmission.

The discharge needles should preferably be exceedingly sharply pointed in order to keep the necessary potentials as low as possible. The reflecting shield should be grounded, and a protecting cage may be provided, to minimize danger from the high potential. In order to make the reproduction distortionless a straight portion of the corona curve must be selected for the operating range, and this is quite feasible because of the character of a corona curve.

I claim:

1. The method of intertransposing sound and electrical energy which includes producing a corona discharge in the air medium which is to carry the sound, and utilizing the relation between air pressure, the heating effect of the corona discharge, and the electrical energy producing it, to obtain intertransposition of sound and electrical energy.

2. The method of translating electrical energy to sound which includes the steps of producing a corona discharge in the air medium which is to carry the sound, and modulating the corona discharge by means of the electrical energy.

3. The method of translating modulated electrical energy to sound which includes us-

ing unmodulated electrical energy to produce a corona discharge in the air medium which is to carry the sound, and modulating the corona discharge by means of the modulated electrical energy.

4. An inertialess device for the intertransposition of sound and electrical energy comprising a corona discharge point and a grounded shield cooperating therewith.

5. An inertialess device for the intertransposition of sound and electrical energy comprising a plurality of corona discharge points and a substantially aperiodic grounded metallic reflecting shield cooperating therewith.

6. An inertialess system for the intertransposition of sound and electrical energy comprising a corona discharge device, and electrical circuit for energizing said device, and means coupled to said circuit in series therewith for the utilization or production of electrical energy fluctuations therein.

7. An inertialess speaker system comprising a corona discharge device, and a source of sound varied high frequency electrical energy coupled to said device to modulate the intensity of the corona.

8. An inertialess speaker system comprising a corona discharge device, an electrical circuit including a source of unmodulated high frequency electrical energy for energizing said device, and a source of sound varied electrical energy coupled to said circuit to modulate the intensity of the corona.

9. In combination, an inertialess speaker comprising a corona discharge device located in the air medium which is to carry the sound, a source of electrical energy for energizing said device at a constant value, a source of modulated electrical energy arranged to modulate the resultant corona, and means for coupling said device and sources electrically in series.

10. In combination, an inertialess speaker comprising a corona discharge device, and means including a radio receiver to energize said device.

11. An apparatus for translating electrical energy into sound which comprises a corona discharge device, a source of alternating current for energizing said device, and means for supplying a modulated high frequency current to said device to modulate the corona discharge.

12. A speaker system according to claim 7 in which said corona discharge device comprises a metallic member provided with a plurality of needle like points and a ground plate.

NILS E. LINDENBLAD.

CERTIFICATE OF CORRECTION.

Patent No. 1,685,075.

Granted September 18, 1928, to

NILS E. LINDENBLAD.

It is hereby certified that error appears in the printed specification of the above numbered patent requiring correction as follows: Page 2, strike out claim 10, comprising lines 102 to 105; same page, lines 106 and 113, for claim numbers 11 and 12, read 10 and 11; and that the said Letters Patent should be read with these corrections therein that the same may conform to the record of the case in the Patent Office.

Signed and sealed this 11th day of December, A. D. 1928.
